UNITED STATES PATENT OFFICE

100,275

DESIGN FOR A TEXTILE FABRIC

Joseph Maharam, New York, N. Y.

Application May 16, 1936, Serial No. 62,668

Term of patent 3½ years

To all whom it may concern:

Be it known that I, Joseph Maharam, a citizen of the United States of America, residing in the Borough of Manhattan, in the city, county, and State of New York, have invented a new, original, and ornamental Design for a Textile Fabric, for which the following is a specification, reference being had to the accompanying drawing, forming part thereof.

The figure is a plan view of a textile fabric showing my new design with a complete design unit enclosed in dot and dash lines.

I claim:

The ornamental design for a textile fabric substantially as shown and described.

JOSEPH MAHARAM.
